UNITED STATES PATENT OFFICE.

ALBERT A. HATTON, OF HALLS, MISSOURI.

ROAD-DRAG.

1,240,714.

Specification of Letters Patent. Patented Sept. 18, 1917.

Application filed January 12, 1917. Serial No. 142,092.

To all whom it may concern:

Be it known that I, ALBERT A. HATTON, a citizen of the United States, residing at Halls, in the county of Buchanan and State 5 of Missouri, have invented certain useful Improvements in Road-Drags, of which the following is a specification, reference being had therein to the accompanying drawing.

The invention relates to a road scraper, 10 and more particularly to the class of machines for planing or smoothing dirt roads.

The primary object of the invention is the provision of a machine of this character wherein the construction thereof permits 15 the smoothing of a road surface and the scraping thereof to render the same in the best possible condition for traffic.

Another object of the invention is the provision of a machine of this character 20 wherein the road surface can be properly leveled with dispatch, the machine being of novel construction, so as to permit the proper adjustment of the cutting blades and scraper board without requiring excessive 25 labor on the part of the operator.

A further object of the invention is the provision of a machine of this character wherein the frame thereof is made rigid to support the cutting and scraping elements 30 which are readily adjustable to assure the efficient leveling of the road to render the same smooth for traffic.

A still further object of the invention is the provision of a machine of this character 35 wherein the scraper for deflecting the loose dirt from the road surface can be properly adjusted angularly to the draft of the machine, so as to deliver the said loose dirt to one side of the road bed during the advancement of the machine.

A still further object of the invention is the provision of a machine of this character which is simple in construction, efficacious 40 in operation, strong, durable, and inexpensive in manufacture.

With these and other objects in view, the invention consists in the features of construction, combination, and arrangement of parts, as will be hereinafter fully described, illustrated in the accompanying drawings, and pointed out in the claims hereunto appended.

In the accompanying drawings:—

Figure 1 is a top plan view of a machine

constructed in accordance with the invention. 55

Fig. 2 is a side elevation thereof.

Fig. 3 is a vertical longitudinal sectional view. 60

Fig. 4 is a rear elevation.

Fig. 5 is a fragmentary perspective view of one front blade and hanger. 65

Fig. 6 is a fragmentary side elevation of the adjustable lever for the hanger.

Similar reference characters indicate corresponding parts throughout the several views in the drawings.

Referring to the drawings in detail, the machine comprises a main frame A formed with skeleton shoes 10, preferably in the 70 form of sleigh runners, made from metal or wood, shod with metal at their treads, although the same may be otherwise constructed, if found desirable.

Connected to the shoes or runners 10 with 75 the top rails thereof, intermediate the same is a cross beam or bar 11, which is fastened to the top rails of said shoes or runners in any suitable manner, while at the rear ends of the latter is a rear cross beam or rail 12, 80 which is also fastened in any suitable manner.

Extending spaced from the front ends of the shoes or runners 10 and to the rear ends thereof are crossed strips or braces 13 which have their rear ends suitably fixed to the 85 end cross beam or rail 12 and their forward ends fixed to the top rails of the shoes or runners 10, and in this manner the frame A is materially braced and rendered rigid.

Fixed to the cross beam 11 spaced from 90 the ends thereof are reinforcing brackets 14, which are also connected to the lowermost rails of the shoes or runners 10, so as to hold the same against lateral displacement and also to reinforce the frame A of the 95 machine.

Arranged longitudinally of the frame A centrally thereof and suitably fixed to the beams or rails 11 and 12 is a main draft bar 15, which is of considerably less length than 100 the shoes or runners 10, the ends of said bar 15 being extended forwardly and rearwardly beyond the cross beams or rails 11 and 12 and at the forward end is mounted a coupling 16 to which is swingingly connected for vertical movement a draft tongue or pole 17, adapted for the hitching or connecting of draft animals thereto, the tongue 105

or pole 17 being fitted with the usual double-tree 18, which is swingingly mounted thereon in any ordinary well known manner.

Connected to the tongue or pole 17, which is materially reinforced at its coupling end, are rearwardly divergent brace rods 19, which are swingingly connected to hangers 20, fixed to the top rails of the shoes or runners 10, and also to the forward ends 10 of the cross braces 13, and these brace rods hold the pole or tongue 17 in longitudinal alinement with the draft bar 15 in the frame A of the machine, and also permit vertical movement of the pole or tongue 15 without sidewise or lateral movement thereof.

Supported forwardly within the frame A below the front portions of the crossed braces 13 are the forwardly divergent or 20 angularly disposed front horizontal cutters or blades 21, which are suspended in working relation to a road bed for adjustment upon hangers, each including the vertical legs 22, slideable through guides 23 in the 25 form of strap loops mounted on the runners 10 and frame A respectively, and the upper connecting rods 24, each leg being formed with a foot 25, which is riveted or otherwise fastened to the blade 21, while the opposite upper end is fixed to the connecting rod 24 in any suitable manner. Carried by the 30 crossed braces 13 between the points of location of the legs 22 are toothed segment racks 26, to which are pivoted operating throw 35 levers 27, the same carrying spring held manually released locking pawls or dogs 28, to engage with the teeth of the segment racks 26, so that the levers 27 can be locked in their adjusted positions.

40 Each throw lever 27 is formed with a curved extension 28', provided with a slot 29, in which is received the connecting pin 30 on the connecting rod 24 between the legs 22 so that on movement of each lever 27 the hanger for the blade 21 will be adjusted to raise or lower said blade relative to the road 45 surface in the operation of the machine, as will be apparent. The horizontal disposition of the cutters or blades 21 will cut the face or surface of the road bed for the assisting in the leveling thereof and rendering it smooth with a perfectly flat surface.

The arms 22 are of a length to permit the cutters or blades to be lowered a slight distance beneath the plane of the treads or runners 10 of the frame A of the machine, so as to assure the proper cutting action thereof on the road bed.

By reason of the angular disposition of 60 the cutters or blades 21, the road bed will be sheared and the cutting action of said blades will be more effective on the advancement of the machine for retarding the latter.

Arranged at the rear end of the frame A 65 is a scraper 31, which is in the form of a

board, and is vertically disposed while mounted on the rearmost face thereof is an arcuate shaped bracket 32, provided with a slot 33 in which is adjustably mounted an eye bearing 34 having pivoted at 35 therein one end of a substantially L-shaped hanger arm 36, which is also pivoted at 37 to a bearing 38, fixed to the main bar 15, the latter being also fitted with a toothed segment rack 39, which has pivoted thereto a throw lever 75 40, carrying a spring held manually released latch 41, which engages with the teeth of the segment 39 to hold the lever 40 in its adjusted position. The lever 40 is formed with a curved extension 42, to which is connected 80 a link 43, the same being also connected to the hanger 36, so that on adjustment of the lever 40, the scraper 31 can be raised and lowered relative to the road bed.

Supported forwardly of the scraper 31 in 35 a bracket 44 on the main bar 15 is a swingle tree 45 having pivoted in the ends thereof trail arms 46, the same being loosely connected to eyes 47 at the upper edge of the scraper 31 the trail arms being rearwardly 90 divergent with respect to each other and on shifting the swingle tree 45 the said scraper 31 can be angularly adjusted for directing the loose dirt acted upon thereby to one side of the machine. The loose connection 95 of the bearing 35 in the bracket 32 permits the angular adjustment of the said scraper 31 on movement of the swingle tree.

Connected to the bottom rails of the runners or shoes 10 at the rear ends thereof are 100 chains 48, each carrying a fastener for detachable engagement with the end of the scraper 31, so as to hold the same against horizontal swinging movement for deflecting the loose dirt to one side of the machine. 105

It will be apparent that on adjustment of the swingle tree 45 the scraper 31 can be reversed in its angular disposition, thereby permitting the dirt to be thrown to either side of the machine when the same is advanced.

Mounted centrally of the frame A is a driver's seat 49, to be occupied by the driver or operator of the machine, the levers 27 being in convenient reach of said driver or operator when keeping the seat to permit manual adjustment thereof for the raising or lowering of the front cutters or blades 21 when the occasion requires.

At the rear end of the frame A and bridging the bar 15 is an outwardly arched guard rail 50, which is fastened to the frame in any suitable manner.

In the operation of the machine, when the same is advanced, the front cutters or 125 blades 21 cut the surface of the road bed to plane the same, and thereby render it straight or flat, while the loosened surface of the road bed is acted upon by the scraper 31, which delivers the same to one side of 130

the machine, and in this manner the road bed is leveled and rendered perfectly smooth, so as to have the same in the best possible condition for traffic.

5 From the foregoing, it is thought that the construction and manner of operation of the machine will be clearly understood, and therefore a more extended explanation has been omitted.

10 What is claimed is:—

1. A machine of the character described comprising a runner frame, forwardly diverging horizontally disposed cutters, hangers supported on the frame and carrying 15 the cutters, means for adjusting the hangers, an angularly and vertically adjustable scraper supported at the rear end of the frame, means for holding the scraper in adjusted position, a swing tree pivoted in

the frame and trail rods pivotally connected 20 thereto and also loosely connected to the scraper.

2. A machine of the character described comprising a frame having side runners and crossed braces, forwardly diverging front 25 horizontal cutters, hangers for supporting the cutters, means for adjusting the hangers to raise and lower the cutters, a center bar in the frame, draft means connected to the center bar, a hanger arm swingingly supported on the center bar, a rear scraper connected for angular adjustment to the hanger arm, means for raising and lowering the hanger arm and means for holding the scraper in its angularly adjusted position. 35

In testimony whereof I affix my signature.

ALBERT A. HATTON.
